Primary Examiner — John R Yeh(74) *Attorney, Agent, or Firm* — Panasonic IP Management; Kerry S. Culpepper(57) **CLAIM**

We claim the ornamental design for an oral waterjet, as shown and described.

DESCRIPTION

FIG. 1 is a front perspective view of our new design for an oral waterjet;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings depict features of the oral waterjet that form no part of the claimed design.
